UNITED STATES PATENT OFFICE.

WALTER RAY GLASSBRENNER, OF CARLINVILLE, ILLINOIS.

APRON.

Application filed April 25, 1923. Serial No. 634,592.

To all whom it may concern:

Be it known that I, WALTER RAY GLASSBRENNER, a citizen of the United States, residing at Carlinville, in the county of Ma-
5 coupin and State of Illinois, have invented a new and useful Apron, of which the following is a specification.

By way of explanation, it may be stated that an apron, and particularly a heavy 10 apron, imposes considerable weight on the neck of the wearer, and upon the shoulders, especially if the apron is made of heavy water-proof material, and is supported by the ordinary neck-yoke.

15 The foregoing being understood, it may be pointed out that this invention aims to provide a means whereby an apron may be held readily on the body of the wearer without placing weight upon the neck or encum-
20 bering the arms.

It is within the province of the disclosure to improve generally and to enhance the utility of devices of that type to which the invention appertains.

25 With the above and other objects in view, which will appear as the description proceeds, the invention resides in the combination and arrangement of parts and in the details of construction hereinafter described
30 and claimed, it being understood that, with in the scope of what is claimed, changes in the precise embodiment of the invention shown can be made without departing from the spirit of the invention.

35 In the accompanying drawings:—

Figure 1 shows in perspective, an apron constructed in accordance with the invention; Figure 2 is a perspective wherein the apron is shown mounted on the body of the 40 wearer; Figure 3 is a section on the line 3—3 of Figure 1; Figure 4 is a perspective view of the spring; and Figure 5 is a rear elevation of the spring.

The numeral 1 marks an apron, fashioned from any desired material and made, sometimes, of heavy water-proof material. The apron 1 is divided at the back to form separable wings 2.

The device embodies a prehensile spring, which is shown in Figure 4, the spring comprising a loop-shaped body, denoted by the numeral 3, and bent upon itself, at its ends, to form rounded projections or eyes 4, the eyes being continued to form upwardly extended converging arms 5 disposed at an angle to the plane defined by the body 3 of

the spring, the arms 5 being bent upon themselves to form rounded bosses or eyes 6 at the free upper ends of the arms.

Any suitable means may be provided for mounting the spring on the apron 1 near or slightly above the waist of the wearer. Thus, the device may include a flexible flap 7 extended circumferentially of the apron 1 and located on the inner surface of the apron, 65 the flap having extensions 8 extended upwardly along the wings 2 at the edges thereof, as shown clearly in Figure 1. Stitching, indicated at 9, connects the lower edge of the flap 7 and the inner edges of the extensions 70 8 with the apron 1, snap fasteners 10 being employed for connecting the upper edge of the flap 7 and the outer edges of the extensions 8 with the apron, so as to form a pocket 11, extended circumferentially of the apron, and extended longitudinally of the apron, along the inner edges of the wings 2 at the upper ends of the wings all of which will be understood readily when Figures 3 and 1 are examined. In the pocket 11 thus constructed, the body 3 of the spring and the arms 5 thereof are held, the body 3 of the spring extending circumferentially of the apron, the arms 5 of the spring extending upwardly along the inner edges of the wings at the top of the apron 1.

The body 3 of the spring tends to hold the apron 1 about the person of the wearer at the waist or slightly above the waist. The arms 5 normally converge, as shown in solid line in Figure 5, but whilst the apron is being placed about the body of the wearer, the arms 5 tend to spring outwardly toward the dotted line position shown in Figure 5. The tendency of the arms 5, therefore, is to draw the upper portion of the apron 1 into the conical form marked by the numeral 12 thereby supporting the apron from the bust, shown in Figure 2 rather than from the shoulders or from the neck.

100 In view of the fact that the spring 3—5 is detachably assembled, in any suitable way with the apron 1, the spring may be removed from the apron, should the apron be made of some material which requires washing, 105 as the term "washing" is usually understood.

Owing to the fact that the eyes or projections 4, of rounded form, are fashioned at the places of juncture between the arms 5 and the body 3 of the spring, the ends of the body 110 3 will be prevented from exerting an uncomfortable pressure on the body of the wearer,

and the bosses 6 at the free ends of the arms have a like function.

What I claim is:—

1. An apron of such length and construction as to terminate well below the neck of the wearer and to be supported independently of the neck, the apron being of such width from end to end that it will practically enclose the body of the wearer circumferentially from one end of the apron to the other, the apron being divided at the back to form wings, and a prehensile spring extended transversely of the apron intermediate the ends thereof, the spring being provided at its rear ends with upstanding arms disposed about at right angles to the plane formed by the spring, the arms extending along the edges of the wings at the upper end thereof.

2. A device of the class described, constructed as set forth in claim 1, and further characterized by the fact that the spring and its arms are removably enclosed in a pocket formed by a strip extended circumferentially of the apron and upwardly along the edges of the wings, one edge of the strip being permanently secured to the apron, and separable fastening means being employed for connecting the other edge of the strip to the apron.

In testimony that I claim the foregoing as my own, I have hereto affixed my signature in the presence of two witnesses.

WALTER RAY GLASSBRENNER.
